Primary Examiner — Catherine Ho*Assistant Examiner* — Tyenne A. Fulton-Crosson(74) Attorney, Agent, or Firm — Grant Attorneys at Law PLLC; Kristin Grant(57) CLAIM

The ornamental design for a shower storage shelf, as shown and described.

DESCRIPTION

FIG. 1 is a right side perspective view of a shower storage shelf;

FIG. 2 is right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The dashed broken lines in the figures illustrate environmental structure which form no part of the claimed design.
